DUMPING MECHANISM FOR TRUCKS.

1,422,077.

Specification of Letters Patent.

Patented July 11, 1922.

Application filed January 24, 1921, Serial No. 439,458. Renewed December 12, 1921. Serial No. 521,925.

To all whom it may concern:

Be it known that I, JOHN A. BEEBE, a citizen of the United States, residing at Omaha, in the county of Douglas and State 5 of Nebraska, have invented certain new and useful Improvements in Dumping Mechanism for Trucks, of which the following is a specification.

This invention relates to mechanism for 10 dumping trucks, and has for its object, broadly, to provide such an arrangement of parts that only a slight force will be required for swinging the box rearwardly or forwardly, means being provided for preventing 15 shocks or undue vibration during the dumping movements of the box, said parts to be few and simple so that manufacture will be economical and operation will be convenient.

The invention consists of the novel construction, combination and arrangement of parts as described herein and claimed, and as illustrated in the accompanying drawings, wherein,—

Fig. 1 is a broken away view showing the 25 rear part of a dumping truck in side elevation, a part of the underframe being removed. Fig. 2 is a transverse section through the box and truck frame on line 2—2 of Fig. 1. Fig. 3 is an end view of the truck. 30 Fig. 4 shows a side view of a hook-moving shaft and its bearings. Fig. 5 is a view showing the position of parts when the box is disposed in dumped position. Figs. 6 and 7 are enlarged details showing the preferred construction of a pivot-plate. Fig. 35 6 is a side view of a pivot-plate, a standard and a part of the underframe of the box being added. Fig. 7 is a plan view of the pivot-plate. Fig. 8 shows a releasing device 40 for the box and its underframe.

Referring now to the drawing, the invention is illustrated in connection with the well known parts of an automobile, such as the rear axle 8, the vehicle frame 9 and 45 springs 10, said springs being disposed above the rear axle and having a yoke 11 mounted thereon.

To utilize these parts for a dumping truck I provide plates 12 adapted to lie upon the 50 ends of the yoke and to be secured thereto and to the spring 10 by any suitable means, as by bolts 13 (Fig. 3.), said plates being provided with pivot-pins 14 (Figs. 6. 7.) which project beyond the ends of the yoke, each 55 pin having a cylindrical part 15 and one of

the pins having a terminal part 16 angular in cross-section for a mounting thereon of a standard α .

I provide a box 17 open at its rear end and provided with an underframe 18, the latter being provided at its lower side with suitable bearings 19 for the cylindrical parts 15 of the pivot-pins 14, and as thus described the box, together with its underframe may have swinging movements on 60 said pivot-pins, the weight being sustained by the springs 10.

Numeral 20 indicates a door or tail gate for making a closure of the rear end of the box, said gate being pivotally mounted at its 65 top in hinge-members 21 carried by the box. In order that the tail gate will be held in closed relation with the box when the latter is disposed in a horizontal position and may swing outwardly when the box is swung 70 rearwardly I provide means which will operate automatically for these purposes, consisting of a shaft 22 (Fig. 4.) provided with hook-arms 23 and having journalled bearings 24 which are provided for the underframe, said shaft being provided at one of its ends with a terminal part 25 which is 75 angular in cross-section.

Numeral 26 indicates an arm which is mounted on the terminal part 25 of the shaft 80 22, and at 27 is indicated a pull-and push-rod pivotally connected at its respective ends with the standard and arm 26, and it will be understood that since the standard will remain stationary while the box has a swinging movement, the center of the arc of said movement being the pivot-pins 14, the shaft 22 will be rotated for moving the hook-arms, the latter being swung upwardly for securing the tail gate in closed relation with 85 the box when the box moves to a horizontal position.

In order that the swinging movements of the box may be under convenient control, I provide mechanism consisting, in 90 part, of a rock-lever 28 having a mounting below the box upon a pivot-member 29 (Fig. 2.) carried by a suitable clip-member or frame 30 which is secured to the vehicle frame 9, forwardly of the pivotal mount of 100 the box, a hoisting-bar 31 being employed which is also disposed below the box and having its upper end mounted to swing from a support 32 carried by the underframe, said bar 31 providing a pivotal connection 105 33, 110

between its ends, for the upper end of the rock-lever 28, the lower end of the bar 31 being pivotally connected, as indicated at 34, with a pull-and-push bar 35 which extends forwardly from the parts mentioned for a pivotal connection 36 with the lower end of a hand-lever 37, said hand-lever being pivotally mounted between its ends, as indicated at 38, upon a bracket 39 carried 10 by the vehicle; and by means of a pawl 40 used in connection with a toothed sector 41, an operator, while on the seat 42, may control the swinging movements of the box, by use of the hand-lever.

15 On account of the particular arrangement of parts and their mounting, as mentioned, the box, when heavily loaded, may be readily and quickly swung rearwardly or forwardly, a very limited force being required for this purpose, and this feature will be appreciated by users of the device.

In order that the swinging movements of the box, by use of the hand lever may be effected with lesser force than would otherwise be required, and that shocks and undue stresses may be avoided, I provide springs to be described, one of these being indicated at 43 having one end secured, as indicated at *a* to a cross-strip rearwardly of the 25 pivotal mounting of the box, its front end being secured, as indicated at *b* to an extension 44 of the rock-lever 28, the action of said spring 43 normally tending to move the extension 44 and lower part of the rock-lever rearwardly, and therefore operating 30 constantly as a force for moving the bar 35 forwardly while the box is disposed in a horizontal position; and therefore a lesser force will be required for swinging the 35 hand-lever 37 rearwardly for moving the box to a dumped position, this being of great advantage in instances when the greater part of a load is at the front end of the box.

40 Numeral 45 indicates a spring having one of its ends connected with the front end of the box, as upon a cross-strip *c*, its rear end being attached, as indicated at *d* to an arm 46 (Fig. 2.) of the rock-lever, said 45 spring not exerting any force while the box is disposed in a horizontal position but operating to resist a movement of the box during the latter part of an upward swinging movement of its front end to thereby prevent shocks or undue vibration, this being 50 of advantage since the rear end of the box often encounters obstructions when swung downwardly, said spring 45 also operating to avoid undue stresses which otherwise 55 might be directed to the pivotal mounting of the box and the levers mentioned. It will be seen that the springs 43 and 45 operate practically independently of each other, one being retracted while the other is actuated, 60 the distance between the mountings *a* and

b for the spring 43, on account of the swinging movements of the rock-bar, being greater when the front end of the box swings upwardly, and the distance between the mountings *c* and *d* for the spring 45 70 being less when the rear end of the box swings downwardly.

In order that the spring 43 may exert a greater or lesser force as an aid in elevating the front end of the box, apertures *e* are 75 formed in the extension 44 at intervals of its length for a connection of the spring 43 therewith.

Since the vehicle or truck may be driven over obstructions, means are provided for 80 maintaining the box in a horizontal position, consisting, in part, of a hook-arm 47 which is pivotally mounted upon the frame 9, as indicated at *f* (Fig. 8.), said hook-arm being adapted to engage a cross-bar *g* which is secured to the underframe 18. By use of a foot-lever 48, pivotally mounted at *h* upon the frame and which may move against the force of a spring *k*, the hook-arm may be released from member *g* to permit dumping, a rock-lever *m* and suitable rods *n* being shown for this connection.

It will be understood that an operator by use of the hand lever may cause a forward movement of the bar 35, the lower end of the hoisting-bar 31 and the upper part of the rock-lever 28 thereby being swung forwardly, the force of the spring 43 aiding in this movement, this operation causing elevation of the front end of the 100 box to the position of parts shown in Fig. 5, the spring 45 not being actuated until the front end of the box has nearly completed its arc of movement. Also it will be understood that when the bar 35 is moved rearwardly by use of the hand lever 37, this movement will be aided by the force of the spring 45, the spring 43 remaining retracted until the front part of the box has completed a part of its downward movement, at which time the spring 43 will be actuated to prevent an undue shock which otherwise might occur by engagement of the cross-bar *g* with the vehicle frame.

110 While I have shown the preferred construction in detail, I do not wish to be understood as limiting myself to exactness in this respect, and changes in form, size, proportion and minor details may be made, these changes being within the scope of the 115 invention as claimed.

I claim:

1. In dumping mechanism, the combination with the frame of a vehicle having a box pivotally mounted thereon, of a rock-lever 125 pivotally connected with the frame, a hoisting-bar pivotally mounted between its ends upon the rock-lever and having its upper end pivotally connected with the box, and a longitudinally movable pull-and-push bar 130

pivots connected with the lower end of the hoisting-bar.

2. In dumping mechanism, the combination with the frame of a vehicle and a box 5 pivotally mounted thereon, of a rock-lever pivotally connected with the vehicle frame, a hoisting-bar pivotally mounted between its ends upon the rock-lever and having its upper end pivotally connected with the box, a 10 pull-and-push bar pivotally connected with the lower end of the hoisting-bar, said pull-and-push bar being movable for increasing the distance between the pivotal connection of the rock-lever with the frame and the 15 pivotal connection of the hoisting-bar with the box, and also being movable for decreasing the distance between the pivotal connection of the rock-lever with the frame and the pivotal connection of the hoisting-bar 20 with said box.
3. In dumping mechanism, the combination with a vehicle frame and a box pivotally mounted between its ends upon said frame, of a rock-lever pivotally mounted 25 on the frame forwardly of the pivotal mounting of said box, a hoisting-bar pivotally mounted on said box forwardly of the pivotal mounting of the box and connected between its ends with the rock-lever, 30 means for increasing the distance between the pivotal mounting of the hoisting-bar and the pivotal mounting of the rock-lever, said means including a movable pull-bar having a mounting upon the hoisting-bar, 35 and a spring connecting the rock-lever with that part of the vehicle box rearwardly of the pivotal mounting of said box.
4. In dumping mechanism, the combination with a vehicle frame and a box pivotally mounted between its ends on said 40

frame, of a rock-lever pivotally mounted on the frame forwardly of the pivotal mounting of the box, a hoisting-bar pivotally mounted on the box forwardly of the pivotal mounting of said box and mounted between 45 its ends on the rock-lever, a pull-bar connected with the hoisting-bar movable for actuating the hoisting-bar and rock-lever, and a spring connected with the rock-lever and said box tending to cause a swinging movement of the rock-lever in one direction, the actuation of the hoisting-bar and rock-lever being for the purpose of elevating the front end of the box.

5. In dumping mechanism, a vehicle frame 55 having a pivotally mounted box thereon, a hoisting-bar connected with the box, a rock-lever connected with the vehicle frame, and a movable pull-bar connected with the hoisting-bar to cause a swinging movement of 60 the hoisting-bar and rock-lever for moving the box in a circle's arc.

6. In dumping mechanism, a vehicle frame having a box pivotally mounted thereon, a longitudinally movable pull-and-push bar, a 65 lever pivotally connected with the frame, a second lever pivotally connected with the first named lever and also pivotally connected with the box, one of said levers being provided with a part extending beyond its pivotal connection with the other lever, said extended part having a pivotal connection with said longitudinally movable pull-and-push bar.

In testimony whereof, I have affixed my 75 signature in presence of two witnesses.

JOHN A. BEEBE.
